US0D1036039S

(12) **United States Design Patent** (10) **Patent No.:** **US D1,036,039 S**
(45) **Date of Patent:** **** Jul. 16, 2024**

(54) **DRAIN PAD**

(71) Applicant: **Zixi Tao**, Linhai (CN)

(72) Inventor: **Zixi Tao**, Linhai (CN)

(**) Term: **15 Years**

(21) Appl. No.: **29/856,160**

(22) Filed: **Oct. 11, 2022**

(51) **LOC (14) Cl.** **07-05**

(52) **U.S. Cl.**

USPC **D32/57**

(58) **Field of Classification Search**

USPC D6/583; D32/35, 55-59
CPC A47L 15/48; A47L 15/481; A47L 19/02

See application file for complete search history.

(57) **CLAIM**

The ornamental design for a drain pad, as shown and described.

DESCRIPTION

FIG. 1 is a front, right and top perspective view of a drain pad, showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is an enlarged view of portion of FIG. 1 thereof.

The dot-dash broken lines depict the boundaries of the enlargements that form no part of the claimed design.

1 Claim, 8 Drawing Sheets
